UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WARP STOP-MOTION FOR LOOMS.

1,350,113.

Specification of Letters Patent. Patented Aug. 17, 1920.

Application filed December 27, 1918. Serial No. 268,562.

To all whom it may concern:

Be it known that I, ALONZO E. RHOADES, a citizen of the United States, residing at Hopedale, in the county of Worcester and 5 State of Massachusetts, have invented an Improvement in Warp Stop-Motions for Looms, of which the following description, in connection with the accompanying drawings, is a specification, like characters on the 10 drawings representing like parts.

The invention to be hereinafter described relates to warp-stop-motions for looms, and more particularly to that type wherein a series of drop devices or detectors are supported by the warp threads, which upon 15 breakage or undue slackness of one or more of said threads, permit such drop devices or detectors to move into position for coöperation with a feeler or vibrator and cause stoppage of the feeler and means actuated thereby to stop the loom.

The passage of the warp threads through the eyes of the detectors and across the rods or rests adjacent the detectors, causes lint 20 or fluff to be deposited upon the parts adjacent thereto. This lint or fluff if allowed to accumulate, is liable to be caught on the warp threads and produce lumps which will increase the danger of breakage of the threads, 25 or result in an impaired woven fabric, and in some cases may render the detectors themselves less sensitive.

Heretofore, the feeler or vibrator has been usually located in a position where the lint, 30 fluff or dirt may gravitate down, accumulate on, and objectionably clog the feeler or vibrator or detectors and parts coöperating therewith. The location of the feeler or vibrator has also been such that ready access 35 cannot be had thereto for the purpose of removing lint, fluff or dirt therefrom.

One of the objects of the present invention, therefore, is to provide a feeler or vibrator mechanism which will automatically 40 tend to remove fluff, lint and dirt from parts adjacent the detectors, and prevent objectionable accumulation thereof.

And another object of the invention is to provide a warp-stop-mechanism which is 45 simple and cheap in construction, and reliable in operation.

With the aforesaid and other objects in view, the character of the invention may be best understood by reference to the following description of one good form thereof 50

shown in the accompanying drawing, wherein:

Figure 1 is a perspective view of a portion of a loom showing the warp-stop-mechanism of the present invention, some of the parts 60 being shown in section;

Fig. 2 is a transverse section affording one view of the feeler operating mechanism; and

Fig. 3 on an enlarged scale is a view somewhat similar to Fig. 2, showing the relation of feelers to detectors, one supported by a warp thread, and the other unsupported by a warp thread.

Referring to the drawing, the loom frame 70 may be of any usual or desired character suitable for the support of the loom parts. Rising from each side of the loom is a stand 1 which may be located between the shedding devices or heddles and the whip roll 75 over which the warp threads pass from the warp beam, said parts being as usual in construction and operation.

Each of the stands 1 carries an end support 3 constituting one form of end frame 80 for the parts of the warp-stop-motion. Extending transversely of the loom and supported at the upper portions of the end supports, are the warp rods 5, over which the warp threads 7 pass and by which they are 85 sustained.

In the present form of the invention, each of the warp threads between the warp rods, sustains a detector or drop device 9, each, in the present instance, in the form of a thin, 90 flat strip of metal containing a warp receiving eye 11, an elongated slot or guide 13, and a notch or recess 15 located preferably a substantial distance above the lower end of the detector. This notch or recess has 95 outwardly divergent top and bottom walls as shown, which allows the feeler to enter and vibrate therein when the detector is suspended by the warp thread even though the warp thread itself by which the detector is 100 suspended may be disturbed in its vertical position by loom vibration or other disturbing causes, as more fully hereinafter described.

Projecting through the elongated slots 13 105 in the detectors are guide bars 17 having their ends detachably secured to the upper ends of the end supports 3. When the detectors are sustained by the warp threads, the upper ends of the elongated slots 13 will 110

- stand above the bars 17, but if a warp thread breaks or becomes unduly slack, the detector for such thread will drop down to the position shown at the right of Fig. 3, 5 where it will be supported by the guide bar. Bridging the loom beneath the warp rods 5, are supports, in the present instance, in the form of bars 19 secured to and carried by the end supports 3. The feelers or vibrators 21, in the present instance of the invention, are in the form of ribbon-like strips having toothed or serrated edges 23, and are located directly above the bridge bars 19. Suitable means may be provided to vibrate or reciprocate the feelers and cause the same alternately to enter and recede from the notches or recesses 15 in the detectors when the latter are sustained by the warp threads. To accomplish this, in the 10 present instance, the ends of the feelers are suitably secured to slides 25 disposed transversely to the supporting bars 19 and adapted to reciprocate in guides conveniently in the form of notches 27 in said bars. Links 25 have ends pivotally connected to pins 31 (Fig. 3) on the slides and opposite ends pivotally connected to pins 33 carried by short arms 35 projecting from bosses 37 fast on a rock shaft 39 mounted in bearings 41 carried by the end supports 3, referred to. Depending from one of the bosses 37 is a long arm 43 connected by a link 45 with an arm 47 fast on a rock shaft 49 journaled in bearings carried by the end supports 3. The construction is such that when the shaft 49 is rocked through the connections described, the slides 25 will be reciprocated and cause vibration of the feelers 21 on the bars 19. The feelers will continue to vibrate so long as the detectors are sustained by the warp threads and the outwardly divergent top and bottom walls of the recess 15 will permit the vibrator or feeler to enter the recess even though the detectors may 45 be disturbed from their normal warp thread suspended positions. Under these conditions the detectors will themselves be moved in a vertical direction or be given a feeler movement so long as they are not sufficiently slack to fully drop the detector, but if a thread becomes broken or unduly slack, the detector therefor will drop to the position shown at the right of Fig. 3, and thereupon will be engaged by the feeler at a point 50 somewhat above the recess 15 in the detector, and prevent further vibration of the feeler. To resist the pressure of the feeler against the detectors, back rests or stops 51 may be 55 provided conveniently in the form of metal strips secured to the upper edges of the bars 19, and in the present instance, having toothed or serrated edges 53. The opposed serrated edges of a back rest and feeler will 60 engage opposed edges of the detectors above the notches or recesses therein and at points substantial distances above the lower ends of the detectors, and effectively prevent twisting or distortion of the detectors from the pressure of the feelers thereon in causing 65 stoppage of the loom.
- The rock shaft 49 referred to, may be operated by any suitable means, such that upon obstruction to its rocking movement, as by the dropping of a detector in front of a feeler to prevent vibration of the latter, said means will actuate the usual shipper lever of the loom and cause stoppage of the latter. As such means and their connections with the shipper are well known in the art, a full illustration thereof is not herein deemed necessary, and for detailed illustration and description of one appropriate form of such means, reference may be had to Letters Patent of the United States, No. 673,824, granted in the name of Edward S. Stimpson, May 7, 1901. As in said patent, the rock shaft 49 has loose and fixed arms f^2 and f^3 , and connections h^2 and h^3 with the coacting parts between these parts and the shipper lever, all of which is fully explained in said patent.
- In the event of breakage or undue slackness of a warp thread, the detector therefor will drop and prevent vibration of the feeler 95 coöperating therewith, and prevent further rocking of the rock shaft 49. This will prevent rocking of the fixed arm f^3 and through the connection h^3 and means, such, for example, as illustrated in the aforesaid 100 patent, will actuate the shipper and stop the loom.
- The continuous reciprocation of the feelers above the upper edges of the bars 19, will continuously tend to remove lint, fluff 105 and dust from the parts, and since the feelers are not beneath the lower ends of the detectors, the spaces between the bars 19 afford free passages to allow escape of the lint, fluff and dust from the loom. The feelers being above the bars 19, and above the lower ends of the detectors, are so located that convenient access may be had thereto, for the purpose of cleaning the same if required.
- The warp-stop-mechanism described is simple and strong in construction, the parts thereof are easily assembled, and reliable in operation.
- Having described one good form of the invention without limiting the same thereto, what I claim as new and desire to secure by Letters Patent is:—
- Claims.
1. In a warp stop motion for looms, the combination of a stand at each side of the loom, end supports secured thereto, bridge bars secured at their opposite ends to the end supports and presenting unobstructed spaces between them for the passage of lint 130

or fluff, a slide mounted on the ends of the bridge bars, feelers secured to the slides and resting on the tops of the bridge bars, a vibrator having a link connection with the 5 slides to reciprocate the feeler over the top of the bridge bars and adapted to remove therefrom any accumulation of lint or fluff, and a series of detectors each having a recess into which the feelers extend when the 10 detectors are supported by the warp threads.

2. In a warp stop motion for looms, the combination of end supports, bridge bars and detector guides secured at their opposite 15 ends to the end supports and presenting unobstructed spaces between them for the free passage of lint or fluff, the opposite end portions of the bridge bars being provided with guiding recesses, slides mounted in the 20 guiding recesses at the ends of the bridge bars, a rock shaft having an arm, a second rock shaft having a link connection with the arm, links connecting the first named rock shaft to each of the slides, feelers extending

between the slides and resting on the top 25 portions of the bridge bars and acting to remove lint and fluff therefrom as they are reciprocated on said bars, and a series of detectors extending between each of the bridge bars and each having a recess for 30 the entrance of the feeler when the detectors are supported by normal warp threads.

3. In a warp stop motion for looms, the combination of bridge bars having an unobstructed space between them through 35 which lint and fluff may pass, feelers mounted for movement over the top of the bridge bars, means including a rock-shaft and link connections for moving the feelers over the 40 bridge bars, and a series of detectors each having a recess with an outwardly divergent wall into which the feelers move when the detectors are supported by non-faulty warp threads.

In testimony whereof, I have signed my name to this specification.

ALONZO E. RHOADES.
